SAFETY MEANS FOR CERTAIN KNITTING MACHINE MECHANISMS

Herbert Erich Haehnel, West Reading, Pa., assignor to Textile Machine Works, Wyomissing, Pa., a corporation of Pennsylvania

Application October 21, 1938, Serial No. 236,164

13 Claims. (Cl. 66—96)

My invention relates to full fashioned knitting machines and more particularly to safety means for use with mechanisms on these machines used to produce transferred, spread, or other modified loop formations.

The ordinary full fashioned knitting machine includes a picot bar in each knitting section having points thereon the principal use of which is to make the picot or lock stitch course in the 10 welt by transferring alternate loops from one needle to the next. However, the picot bar operates in the same zone as the narrowing combs and it is common practice to throw the picot bar up to a rest position as soon as the picot 15 course has been made and to swing it down to active position again soon after work has started on a new welt. Owing to the desire for large output, the operatives are hurried in placing the picot bars in active and rest positions and sometimes fail to register or mesh the guide members 20 on the rod by which the picot bars are pivotally mounted with the fixed guide members with which they are intended to cooperate.

Also, the guide members may stick, one in 25 the other, and hold the picot bars out of the correct longitudinal position even when they are in the correct angular position and the guide members are in mesh.

It is an object of my invention to provide a 30 means whereby damage is prevented in case the point bar is not properly engaged by the usual guide means at the time the point bar is dipped.

Another object of my invention is to provide an 35 automatic means to swing the loop manipulating points out of the way of the knitting needles in case the guides for the point bars are not engaged.

It is another object of my invention to provide 40 means whereby the operative may place the point bar or bars of a knitting machine into active position much more quickly and accurately as compared to the arrangement ordinarily used.

Another object of my invention is to provide 45 means whereby a relatively high pressure may be applied to the pivoted point rod to prevent its sticking in a position axially removed from the normal active position.

It is a well known procedure to hold the point 50 bars in rest position beneath a rail by a spring latch acting on a collar on the pivoted rod or shaft on which the point bars are mounted. However, such latch means has not been altogether satisfactory in that it has permitted the rod and bars to vibrate sufficiently at times when

in rest position to damage the points by striking against the guard rail.

It is a further object of my invention to provide an improved latch means for the point rod adapted to substantially prevent it from vibrat- 5 ing.

With these and other objects in view, which will become apparent from the following detailed description of the illustrative embodiment of the invention shown in the accompanying 10 drawings, my invention resides in the novel elements, features of construction and arrangement of parts in cooperative relationship as herein-after more particularly pointed out in the claims.

My invention is adapted to carry out the objects aforesaid in any knitting machine which comprises a narrowing machine having a pivoted rod thereon fixed to which is or are one or more point bars, but which otherwise may be of any known or desired type. Said narrowing machine may be equipped as desired with any or all of the parts usually associated with the picot bar and the rod therefor such as, the guide means for determining the correct angular position of the rod for cooperation between the picot points and the knitting needles; the spring means tending to throw the picot rod into correct longitudinal position for cooperation between the points and needles; adjustable means for limiting the movement of the picot rod in response to said spring means; a guard rail; and a handle for swinging the picot rod. An arrangement according to my invention comprises a yielding means arranged to turn the shaft on which the picot, lace, non-run bars, or the like, are mounted to throw said bars in the direction to carry the points out of the path of the knitting needles. Preferably said yielding means comprises a spring and the necessary connections to permit it to act in the desired manner. Such spring, however, is not to be confused with the coil spring ordinarily provided on the lock stitch rod of a full-fashioned knitting machine. Other specific features for carrying out the objects herein set forth are noted in the following description. 45

In the drawings:

Figure 1 is a front elevational view of a portion beginning at the left of a full-fashioned knitting machine legger having my improvements applied thereto; 50

Fig. 2 is a transverse sectional view of the machine taken near the right hand end of Fig. 1;

Fig. 3 is a fragmentary view on an enlarged scale of a portion of the right hand part of Fig. 55

1 with certain of the parts being shown in different positions;

Fig. 4 is a view similar to Fig. 3, but showing the parts in different relative positions;

5 Fig. 5 is a fragmentary sectional view, on an enlarged scale, taken substantially on the line 5—5 of Fig. 3;

10 Fig. 6 is a view similar to Fig. 5 but showing the parts in different relative positions and having certain parts broken away for purposes of illustration;

15 Fig. 7 is a fragmentary sectional view taken substantially on the line 7—7 of Fig. 1;

Fig. 8 is a fragmentary sectional view through 15 a portion of the narrowing machine, taken substantially on the line 8—8 of Fig. 1, illustrating one of the stop means for the lock stitch shaft; and

20 Fig. 9 is a fragmentary sectional view taken substantially on the line 9—9 of Fig. 1 and illustrating one of the latch means for the lock-stitch shaft.

25 In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines," copyright 1920, and in the "Reading" Full Fashioned Knitting Machine Catalogues, copyright 1929 and 1935, published by the Textile Machine Works, Reading, Pennsylvania, and in a pamphlet entitled "Knitting Machine Lectures," published in 1935 by the Wyomissing Polytechnic Institute, Wyomissing, Pennsylvania.

30 The machine illustrated in Figs. 1 and 2 of the drawings comprises a frame 10 on which are mounted the usual main cam shaft 11, pattern chain 12, cam shaft shifting mechanism 13, needle banks 14, narrowing head 15, narrowing nuts 16, and narrowing rods 17. Said rods 17 form part of the usual narrowing machine which 35 comprises a rear shaft 18 and a front narrowing shaft 19 from which rods 17 are supported by brackets 20 (Figs. 5—9). The rear narrowing shaft 18 is pivoted in the frame and connected to the front narrowing shaft 19 by heavy curved arms 21 (Figs. 1 and 2), the front shaft 19 being supported from the cam shaft 11 by links one of which appears at 22. Links 22 connect by pivots at their lower ends to levers 122 which carry rollers one of which appears at 23 and which rests 40 during normal knitting on a circular disk 24 on shaft 11. When shaft 11 is shifted to the right, as viewed in Fig. 1, by the action of the chain 12 in throwing the cam shaft shifting mechanism 13 into operation, rollers 23 are brought 45 onto cams 25, also on shaft 11, one of which is companion to each disk 24. The operation of cams 25 causes the front narrowing shaft 19, and with it all parts supported therefrom, to dip twice with each revolution of the cam shaft 11.

50 In addition to the rods 17, the brackets 20 support from the front narrowing shaft 19 the lock stitch or picot rod or shaft 26 (Fig. 5), arranged in two parts or halves, the division between which appears clearly in Figs. 3 and 4.

55 Arms 127 fixedly connect shaft 26 to point carrying bars 27, which are adapted, when the bars are lowered and otherwise in correct position, to lift knitted loops from the needles of banks 14 when shaft 19 is dipped and raised by the cams.

60 Flars 27 are shown in Figs. 4 and 6 in the correct

or active position in which the points thereon are able when dipped to properly lift knitted loops from the knitting needles, shaft 26 having a collar 42 thereon to determine the proper longitudinal position of the shaft for dipping the points. When the usual narrowing combs (not shown) supported from rods 17 are to be used, picot bars 27 are swung up into the rest position shown in Figs. 1, 2 and 8 in which the picot points are not only out of the way of the narrowing combs, but are protected by a rail 126 fixed to the shaft 19. In order to promote the end that the bars 27 shall arrive at the correct position prior to the dipping of shaft 19, the ordinary picot shaft has thereon a number of guide levers 15 or arms 28 (Figs. 1, 3 and 9), which have off-set ends provided with grooves 29 therein designed to embrace lips 30 projecting downward from brackets 20 when levers 28 are moved longitudinally of the machine in a certain plane. To facilitate bringing the grooves of arms 28 into alignment with projections 30, the connecting arms 127 between the shaft 26 and a lock stitch bar 27 have therein an adjustable stop bolt 148 (Fig. 8) which strikes a rod 129 fixed on the narrowing machine to stop bars 27 and arms 28 in the desired plane. When the grooves 29 and lip 30 are properly aligned, the picot shaft 26 may be pushed downwardly by handle 31 (Fig. 4) and longitudinally by the spring and lever means 32 (Fig. 1) to engage the lips in the grooves to prevent angular movement of bars 27 on shaft 26 during the loop shifting operations. When fully pushed home in the longitudinal direction, the shaft 26 holds the bars 27 so that the points at the one ends of the bars lie directly above the needles at the same ends of the needle banks. It often happens, however, that the ends of arms 28 strike the lips 30 thereby preventing proper coaction between the points and the needles. 40 If the operative does not notice this and allows the bars 27 to be dipped when their points are improperly positioned relative to the needles, a damaging smash may occur. In accordance with my invention, yielding means is provided to 45 swing the bars 27 up into the position shown in Fig. 5, in which the points in bars 27 are out of the path of the knitting needles, unless the lips 30 are engaged in grooves 29. The means illustrated for this purpose comprises a helical spring 51 connected at one end to the upper end of a vertical arm 52 which is clamped to the front narrowing shaft 19, and arm 52 carries a pin 53 near its upper end whereby the upper end of spring 51 is secured to the arm. The lower end of spring 51 is secured to a band 54 which passes around a collar 55 fixed on shaft 26, as shown in Figs. 5 and 6, and is fastened to the cylindrical face of the collar so that spring 51 tends to lift bars 27 away from needle banks 14. Also, 50 spring 51 is made strong enough to lift bars 27 and to support them as shown in Fig. 5 in position in which their points will not strike the needles or damage themselves if dipped. Further, when the bars 27 are held in the position 55 of Fig. 5, the attention of the operative is usually drawn to the fact that the bars are not properly placed, and does not start the machine until they are so.

55 In order to facilitate entering lips 30 in grooves 70 29, I have provided a handle or lever 33 (Figs. 3 and 4) pivoted on a bracket 34 also fixed on shaft 19. The pivot of lever 33 is so arranged that pressure applied to its upper handle end is multiplied at its lower end. The lower end of lever 33 75

carries a laterally projecting boss 35 lying between and arranged to bear against either of two collars 36 on shaft 26. When the upper end of lever 33 is swung to the right, as viewed from the front of the machine, the boss 35 bears against the left hand collar 36 and throws shaft 26 to the left. Lever 33 has a latch pin 37 thereon controlled by a latch handle 38 whereby the pin 37 can be pulled from and allowed to enter either one of two holes 39, 39 in the upper end 40 of bracket 34. When pin 37 is in the right hand hole 39, shaft 26 is held so far to the left that arms 28 do not touch brackets 20 or lips 30 and the operative can make sure the arms and lips are in approximately the same plane by pressing on handle 31. If now, handle 33 is swung over so that pin 37 is in the left hole 39, the operative may rest assured that the lips 30 have been embraced in grooves 29. He can also assure himself that the lock stitch shaft 26 has been pushed to the right the full distance by pressing against handle 31.

Of course, when pin 37 is in the left hand hole 39, the shaft 26 is nearly the full distance to the right to align the points with the knitting needles, but a clearance sufficient to permit proper operation of the points is required between the boss 35 and the right hand collar 36 because the shaft 26 is shifted longitudinally at the time of transferring stitches by a wedge 41, pivotally mounted on the front narrowing shaft 19, which is brought down between the two halves of shaft 26 at the proper times. The movement of wedge 41 is accomplished in the usual manner by the cam 141 (Fig. 2) and linkage mechanism 142. It is apparent that the left hand half of shaft 26, the one principally illustrated, is shifted to the left by the action of wedge 41. Therefore, the right hand collar 36 is set to provide the required clearance between said boss and collar when the points and knitting needles are in proper alignment for the points to pick up loops from the needles. However, if the left half of shaft 26 has moved enough to the right so that pin 37 may enter the left hand hole 39, the spring of means 32 (Fig. 1) will almost certainly throw the shaft the full distance to the right so that the usual adjustable collar 42 on shaft 26 will strike its stop 143, the collar 42 and stop 143 being set to ensure that the points and knitting needles will be in alignment when the collar and stop are in contact provided the angular position of shaft 26 is correct as provided for by engagement of lips 30 in groove 29.

After a loop transferring operation of point bars 27, when it is desired to swing the bars up to their rest position, the left half of shaft 26 is shifted to the left from the position as viewed in Fig. 4, to the position shown in Figs. 1 and 3, to disengage the lips or projections 30 from grooves 29. In accordance with the present invention, this can be done very conveniently by swinging lever 33 until pin 37 enters the right hand hole 39. The shaft 26 is thereby latched in a position in which point bars 27 can be swung up to rest position without chance of mechanical interference between any of the parts. The left hand collar 36 is then in engagement with the boss 35, but this does not prevent shaft 26 from swinging readily. To prevent the points in bars 27 from striking rail 126 when the bars 27 are swung up to rest position, an arm 140 (Fig. 8) is fixed to shaft 26 in position to act as a stop to the motion of the shaft toward rest position by striking shaft 19.

As shown also, a catch is provided for holding the shaft positively in rest position. The arrangement shown for this purpose (Fig. 3) comprises a catch member 43 having an apertured lug 44 at one end, the left end as seen in Fig. 3, whereby the member 43 is pivoted on rail 126 so as to swing in contact with the rear vertical side of the rail 126. A pin 46 passes through member 43 beneath the lower edge of rail 126 parallel to the axis of member 43 and as close to such axis as convenient, pin 46 acting both as a stop to prevent member 43 from being lifted too far and as a means whereby a spring 47 is connected between member 43 and a point on rail 126 to hold member 43 in its lower position as shown in Figs. 3 and 4. As the bars 27 are swung up, the outer end of one of arms 28 strikes the catch member 43 and pushes it up, or else it may be lifted by the finger piece 45, so that the arm 28 passes behind piece 43. The spring 47 thereupon draws the piece 43 down in front of the end of the arm 28, thereby positively latching the arm in the position shown in Fig. 7. It will be noted that member 43 holds bars 27 against turning in one direction only and that it does not prevent the points in bars 27 from striking rail 126.

In accordance with my invention, other arms 28 are latched at the same time as the arm engaged by member 43 and, although not so positively, against movement in either direction. This is accomplished by means including horizontal spring plates 48 (Fig. 9) which are attached to vertical arms 49 fixed to the front narrowing shaft 19. Spring plates 48 are bent at their forward free ends to engage in grooves 50 in the outer ends of arms 28 whereby an additional latching action is provided at various points along the shaft 26. It is an important advantage of my invention that the spring latch plates 48 act on arms 28 at their outer ends and therefore at a considerable distance from shaft 26. The latch means therefore have the maximum leverage and hold the shaft in rest position with minimum vibration. The points in bars 27 are thereby preserved from damage which might be caused by vibrating enough under the present-day high speeds to strike guard rail 126.

When the time arrives for the next loop lifting operation of bars 27, the positive latch member 43 is lifted by hand to release the arm 28 which cooperates therewith and a pull on bars 27 or handle 31 will then dislodge the other arms 28 from spring latch plates 48 and permit bar 27 to be lowered and brought to operating position as above described.

While it has been usual to provide means for holding the bars 27 in their lowered position, my spring 51 performs the function of balancing part of the weight of bars 27 and of the arms attached to shaft 26 both in raising and lowering bars 27, and of holding the points out of the way of the needles when the bars are lowered, but not locked in their operative position.

With the points held out of the way of the needles by the spring 51, if the operative moves the handle 31 to the left as viewed in Fig. 4, the arms 28 will be positioned in front of their respective brackets 20, whereupon the spring 51 will maintain the points in the position of Fig. 5. Furthermore, if the operative, upon pressing the handle 31 downwardly does not align the notch 28 of the arm 28 with the lip 30 of the bracket 20, the arm 28, upon being moved to the left by the lever 33, will engage the side of the bracket 20 thereby preventing the lever from being

latched in its left position; thus, upon release, the handle will be biased to the right by a spring 56, as shown in Fig. 3, whereupon the spring 51 will immediately raise the points to the position of Fig. 5, in which position the points are out of the way of the needles.

From the foregoing it will be seen that my spring means 51 cooperates closely with the shaft shifting lever 33 and latch handle 38 in preventing damage to the points and needles in that whenever the operative swings bars 27 down and pushes the shaft 26 toward the center of the machine almost or wholly as far as necessary to bring the points into their correct axial positions for transferring stitches and places the latch pin 31 of lever 33 in the left hand hole 39 of the bracket 34, but the parts 30 are not engaged in the grooves 29, the spring 51 is able to swing shaft 26 to raise the points in bars 27 out of the way of the knitting needles and thereby prevent damage to the machine.

Of course, the improvements specifically shown and described by which I obtain the above results, although illustrated and described in connection with the well known picot attachment, is obviously adapted for use with other rod operating mechanisms and can be changed and modified in various ways without departing from the invention herein disclosed and hereinafter claimed.

30 I claim:

1. In a full fashioned knitting machine having knitting needles, in combination, a point bar having points for cooperating with the knitting needles and mounted to swing on a pivoted rod from an active to a rest position, said rod mounted to move also longitudinally of its axis, means arranged to multiply pressure applied to it and to assist in moving said bar into the correct longitudinal position for cooperation with the needles, and means for latching said means approximately in the position corresponding to said correct position of said bar.

2. In a full fashioned knitting machine having knitting needles, the combination of a point bar having points for cooperation with the needles and mounted to swing on a pivoted rod from an active to a rest position, said rod mounted to move also longitudinally of its axis, a lever arranged to multiply pressure applied to it and pivoted to assist in moving the rod into the correct position for cooperation between the points and the needles, and means for latching said lever in a position insuring that the point bar is approximately in the correct longitudinal position for the points to cooperate with the needles.

3. In a full fashioned knitting machine having knitting needles, the combination of a point bar having points for cooperation with the needles and mounted to swing on a pivoted rod from an active to a rest position, said rod mounted to move also longitudinally of its axis, latch means including an arm fixed to said rod arranged to latch said rod and bar against angular movement in the lower position of the bar by longitudinal movement of the rod, and a second latch means including a groove in the end of said arm arranged to latch the rod against angular movement in the rest position of the bar.

4. In a full fashioned knitting machine having knitting needles, the combination of a point bar having points for cooperation with the needles and mounted to swing on a pivoted rod from an active to a rest position, said rod mounted to move also longitudinally of its axis, an arm mounted to swing in unison with said bar and

having a groove in one face forming part of a means for holding said bar in its proper angular position for cooperation with the needles, and a groove in another face of said arm forming part of a means for holding said bar in its rest position and for preventing vibration thereof in said position, and means arranged to multiply pressure applied to the rod and to assist in moving said bar into the correct longitudinal position for cooperation with the needles.

5. In a full fashioned knitting machine, the combination as set out in claim 4 and in which the means for preventing vibration includes a leaf spring engaging the second groove.

6. In a full fashioned knitting machine having knitting needles, the combination of a point bar having points for cooperation with the needles and mounted to swing on a pivoted rod from an active to a rest position, a band fixed at one end to said rod and curved thereabout, and a spring fixed to the other end of said band and adapted and arranged to support said bar in a position intermediate its active and rest position.

7. In a full fashioned knitting machine, the combination as set out in claim 6 together with a collar fixed on the rod intermediate the band and the rod.

8. The combination in a full fashioned knitting machine of an axially shiftable shaft having points supported therefrom, knitting needles for cooperating with said points in the production of modified loops, a collar on said shaft, a hand lever arranged to act on said collar to press said shaft approximately to the proper axial position for the production of modified loops, means to latch said hand lever in the position corresponding to said approximate position of the shaft, a latch means having interengaging parts adapted to hold said shaft in the proper angular position for the production of modified loops, and resilient means for swinging said shaft to prevent contact between said points and needles when said parts are not engaged.

9. In a full fashioned knitting machine having knitting needles, the combination of a point bar having points for cooperation with the needles and mounted to swing on a pivoted rod from an active to a rest position, said rod mounted to move also longitudinally of its axis, latch means for releasably holding said bar in rest position comprising an arm fixed on said rod engaging with a part having an end rigidly secured relative to the pivot of the rod, and a second latch means for holding the bar in active position and releasable by a longitudinal movement of said pivoted rod, which also includes the arm fixed to the rod and forming part of the latch means acting in the rest position, and means arranged to multiply pressure applied to the rod and to assist in moving said bar into correct longitudinal position for cooperation with the needles and to longitudinally move said rod to release said latch means.

10. In a full fashioned knitting machine having knitting needles, the combination of a point bar having points for cooperation with the needles and mounted to swing on a pivoted rod from an active to a rest position, said rod mounted to move also longitudinally of its axis, means arranged to multiply pressure applied to the rod and to assist in moving said bar into the correct longitudinal position for cooperation with the needles and yielding means so arranged with respect to said rod as to swing it part way from active toward rest position when the bar is not in

its correct longitudinal position and adapted to hold the bar and its points out of the way of the needles if the bar is dipped when free.

11. In a full fashioned knitting machine having knitting needles, the combination of a point bar having points for cooperation with the needles and mounted to swing on a pivoted rod from an active to a rest position, said rod mounted to move also longitudinally of its axis, means arranged to multiply pressure applied to the rod and to assist in moving said bar into correct longitudinal position for cooperation with the needles, and yielding means so arranged with respect to said rod as to swing it part way from active toward rest position when the bar has not been moved to said correct longitudinal position.

12. In a full fashioned knitting machine having knitting needles, the combination of a point bar having points for cooperation with the needles and mounted to swing on a pivoted rod from an active to a rest position, said rod mounted to move also longitudinally of its axis, means arranged to multiply pressure applied to it and to assist in moving said bar into correct longi-

tudinal position for cooperation with the needles, means for latching said means approximately in the position corresponding to said correct position of said bar, and yielding means so arranged with respect to said bar as to swing it part way from active toward rest position when the bar has not been moved to said correct longitudinal position.

13. In a full fashioned knitting machine having knitting needles, the combination of a point bar having points for cooperation with the needles and mounted to swing on a pivoted rod from an active to a rest position, said rod mounted to move also longitudinally of its axis, latch means including an arm fixed to said rod arranged to latch said rod and bar against angular movement in the lower position of the bar by longitudinal movement of the rod, means arranged to multiply pressure applied to it and to assist in moving said rod longitudinally, and a second latch means including a groove in the end of said arm arranged to latch the rod against angular movement in the rest position of the bar.

HERBERT ERICH HAEHNEL. 25
